DESIGN FOR A HAND TRUCK

Alvin H. Beidelman, Jr., Naperville, Ill.

Application November 26, 1945, Serial No. 124,082

Term of patent 14 years

(Cl. D14—3)

To all whom it may concern:

Be it known that I, Alvin H. Beidelman, Jr., residing at Naperville, in the county of Du Page and State of Illinois, have invented a new, original, and ornamental Design for a Hand Truck, of which the following is a specification, reference being had to the accompanying drawing, forming part thereof, in which:

Fig. 1 is a perspective view and Fig. 2 a front elevational view of a hand truck embodying my new design.

In the illustration of Fig. 1, a portion of the lefthand handle of the hand truck, which is identical with the righthand handle, has been broken away for convenience of illustration.

I claim:

The ornamental design for a hand truck, substantially as shown.

ALVIN H. BEIDELMAN, JR.
